C. F. HARMAN.
POCKET CASE.
APPLICATION FILED DEC. 3, 1913.

1,129,485.

Patented Feb. 23, 1915.

UNITED STATES PATENT OFFICE.

CHARLES F. HARMAN, OF ENTERLINE, PENNSYLVANIA.

POCKET-CASE.

1,129,485.

Specification of Letters Patent. Patented Feb. 23, 1915.

Application filed December 3, 1913. Serial No. 804,457.

To all whom it may concern:

Be it known that I, CHARLES F. HARMAN, a citizen of the United States, residing at Enterline, in the county of Dauphin and State of Pennsylvania, have invented certain new and useful Improvements in Pocket-Cases, of which the following is a specification, reference being had to the accompanying drawings.

This invention relates to new and useful improvements in pocket cases and more particularly to a case which is preferably in the form of a wallet, the object of the invention being to provide a pocket case which can be readily fitted out as a first aid wallet or can be readily used as a traveler's case or a sample wallet and is also so constructed that it may be readily used for various purposes of the above character.

Another object of the invention is the provision of a pocket case of the above character which will possess advantages in points of efficiency and durability, is inexpensive to manufacture and at the same time is simple in construction and operation.

With the above and other objects in view, the invention consists in the novel features of construction and the combination and arrangement of parts to be hereinafter more fully described, pointed out in the claims, and shown in the accompanying drawings, in which—

Figure 1 is a detail perspective view of a pocket case constructed in accordance with my invention; Fig. 2 is a longitudinal sectional view; Fig. 3 is a detail elevation of the inner case; Fig. 4 is an elevation of one of the end flaps of the outer case.

In carrying out my invention, I provide a single piece of material, as indicated at 1, which may be of leather or any other desired material. The body 1 of my improved pocket case is preferably elongated in form and is provided at one end with a tapering portion 2 having a resilient socket 3 at its outer end which, when the case is in a folded position is adapted to engage with a catch 4 formed upon the outer side of the body 1 at the opposite end thereof. Secured to the end of the body opposite the flap 2 is a transversely extending piece 5 which is secured at one of its longitudinal edges and at both ends thereof by sewing, as indicated at 6, to form a suitable pocket whereby papers, cards and various other articles of this character may be kept.

Secured transversely across the central portion of the body is a second strip 7 which is secured at one of its longitudinal edges and at its ends by sewing, as at 8, to form a central pocket for the reception of bills and the like. Secured to the outer face of the strip 7 which forms a central pocket is a strip 9 which forms a pocket smaller in size than the pocket formed by the strip 7 and is adapted for the reception of calling cards and similar articles of the like character. To the outer side of the strip 9, I secure a plurality of leather strips which form a suitable frame 10 in which is adapted to be disposed an identification card, as illustrated at 11, and arranged within the frame and disposed over the card is a piece of transparent material whereby the card will be protected against the usual wear from the opening and closing of the pocketbook, but at the same time is clearly visible through the transparent cover.

In conjunction with my improved pocket case, I provide a vial retainer which is in the form of an elongated body 12 having upon its longitudinal edges at a central point the outwardly projecting flaps 13 and 14, the flap 14 being somewhat longer than the flap 13 and provided at its outer end with a suitable catch 15 adapted for engagement by the resilient socket 16 to securely retain said flaps in position over the vial retainer. Secured to the central portion of the body 12 by sewing the same at its end portions is a supporting strip 17, thus spacing the strip from the body 12 so that absorbent cotton, bandages and similar articles may be inserted between the body and the strips.

Secured to the outer face of the strip 17 is a longitudinal strap 18 which is secured at each of its ends and at various intervals throughout its length to provide the loops 19 whereby vials or various instruments and articles may be inserted within said loops to retain the same within the wallet. The end flap 20 of the body 12 is provided with spaced resilient sockets 21 which are adapted to engage the catch members 22 formed upon the outer side of the flap 23 when the body 12 is in its folded position. The body 12 is provided at its central portion with the spaced resilient catch members 24 which are adapted for engagement within the resilient sockets 25 which are carried by the strip 5 upon one end of the body 4 so that

when it is desired to fold the two sections of the wallet together, the catches 24 are engaged within the sockets 25 and the body 1 of the main portion of the wallet is folded 5 around the folded body 12.

From the above description taken in connection with the accompanying drawings, it will be readily apparent that I have provided a simple and durable pocket case 10 which not only provides a suitable wallet for the reception of vials, paper money, cards and various articles of the like character but also provides a case for the reception of first aid articles such as medicine 15 vials, cotton, bandages and small instruments, if desired.

The device as herein shown and described is constructed of leather but it is understood that the case may be formed of any 20 suitable material and may be used for purposes other than described herein. The device in itself is extremely simple in construction and can be manufactured at a comparatively low cost.

While I have shown and described the preferred form of my invention, it will be obvious that various changes in the details of construction and in the proportions may be resorted to for successfully carrying my 30 invention into practice without sacrificing any of the novel features or departing from the scope of the appended claims.

What I claim is:—

1. A device of the class described including an elongated body portion, a transversely extending strip arranged across one 35

end of the body and having both ends and one of its longitudinal edges rigidly secured to the body, whereby to form a pocket, socket members carried by said strip, an auxiliary body member including foldable strips, catch members carried by the auxiliary body and adapted to engage the sockets on said strip and the opposite end portion of the main body being adapted to 45 fold over the auxiliary body, as and for the purpose set forth.

2. A device of the class described including an elongated body member, socket members carried by one end of said body member, an auxiliary body, catch members carried by said auxiliary body and adapted for engagement with the socket members on the body, whereby to removably secure the auxiliary member to the body, a supporting strip secured to the auxiliary body, a longitudinal strip secured to the supporting strip and adapted to be secured to said supporting strip at various intervals throughout the length of the same to provide loops, inter-folding flaps adapted to engage over said strips, and means whereby to secure the same in position, the free end of the main body being adapted to fold inwardly over the auxiliary body to entirely inclose the 60 same, as and for the purpose set forth.

In testimony whereof I hereunto affix my signature in the presence of two witnesses.

CHARLES F. HARMAN.

Witnesses:

JOHN D. HARMAN.

EDWARD E. HOGE.
